UNITED STATES PATENT OFFICE.

LOUIS PHILIBERT GOFFIN AND EVARISTE VANRIET, OF BRUSSELS, BELGIUM.

SECURING RAILWAY-RAILS TO METAL SLEEPERS.

SPECIFICATION forming part of Letters Patent No. 368,714, dated August 23, 1887.

Application filed April 27, 1887. Serial No. 236,381. (No model.) Patented in Belgium September 24, 1886, No. 74,626.

To all whom it may concern:

Be it known that we, LOUIS PHILIBERT GOFFIN and EVARISTE VANRIET, both residing at Brussels, in the Kingdom of Belgium, 5 have invented certain new and useful Improvements in Securing Railway-Rails to Metal Sleepers, (for which we have received Letters Patent of Belgium, dated September 24, 1886, No. 74,626,) of which the following is a full, 10 clear, and exact description, reference being had to the accompanying drawings, forming part thereof.

Our invention relates to a peculiar system of rail attachment for fixing railway-rails to metallic longitudinal or cross sleepers; and it 15 consists of the use of an angularly-movable resting or bearing plate, A, in combination with two lock-pieces, B and C, and a wedge or key D. (See Figures 1 and 3, which are respectively a sectional view on the line 1 2 of Fig. 2 and a sectional view on the line 1 2 3 4 of Fig. 4.) These different parts are arranged and combined in such a manner that when the resting or bearing plate A is placed under 20 the rail-foot in a position parallel thereto, Figs. 1 and 2, one of its lock-holes, of oblong form, shall coincide with a similar opening in the sleeper and permit of the introduction of the outer lock-piece, B, which is then 25 displaced until it is almost in contact with the end of the lock-hole. Then, by means of a lever, the sleeper and the resting-plate are applied against the lower surface of the rail. By then turning the resting-plate, by striking 30 it with a hammer until it is in its normal position perpendicular to the rail, its angular motion is also imparted to the outer lock, B, which, by turning on its vertical axis, gradually and very tightly pinches the rail-foot 35 and can no longer be removed.

In the normal position of the resting-plate A, indicated in Figs. 3 and 4, another hole in the same coincides with a corresponding hole in the sleeper situate on the inner side of the 40 rail, and now permits of the forced introduction of the inner lock-piece, C, whereby an energetic traction is exerted by means of the resting-plate A on the external lock-piece, and the pinching action of the same is increased.

50 The inner lock-piece is then entirely secured in its position by driving a suitably-shaped key, D, between the free part of its head and

the resting-plate until perfect fixing of the rail is effected.

The resting-plate A, Fig. 3, may have a 55 uniform thickness or a decreasing one, so as to present an inclined surface corresponding with the inclination to be given to the rails.

The outer lock-piece, B, Figs. 3 and 5, resembles in its section a double-headed bolt 60 suitably shaped for adapting itself to the shape of the rail-foot. Its upper head is enlarged, so as to offer a sufficient surface of contact. Its shank is at N, Fig. 5, of a section shown, Fig. 7, so as to permit of free motion in the hole 65 in the sleeper, and at M, Fig. 5, of a section shown, Fig. 6, so as to compel the lock-piece to follow the angular motion of the resting-plate.

The inner lock-piece, C, Figs. 3 and 8, which 70 may be replaced by any other contrivance or lock, if desired, possesses a single head of special shape, so as to bear on one side against the rail-foot, whereas on the other side it leaves between it and the resting-plate a certain opening for the reception of the key D. The shank of this inner lock-piece is bent at 75 its lower end, so as to bear against the under surface of the sleeper. The upper heads of the lock-pieces are made hollow or grooved 80 out, so as to resemble in their section a T, whereby their weight is diminished without diminishing their resistance.

The key D, Fig. 9, is straight or slightly inclined, and is wedge-shaped at one end and reinforced at the other. It is, moreover, provided with one or more ribs, which are engaged in corresponding slots in the lock-piece.

The arrangement described above permits of the rails being secured on the external side 90 without displacing the same, and on the inner side by the simple effect of the key.

When the rail ends are supported, lock-pieces of larger dimensions may be employed at the joints, so as to secure two abutting rail ends at the same time; or a lock-piece of greater dimensions may be used outside the rails, and two lock-pieces on the inner side, one for each rail driven into holes conveniently spaced apart.

Having fully described our invention, what we desire to claim and secure by Letters Patent is—

1. The railway-tie, perforated as described,

and an angularly-movable resting - plate, A, provided with two lock-holes, in combination with two lock-pieces, B C, and a wedge or key, D, the arrangement being such that in the 5 first position of the resting-plate, parallel to the rail, one of its lock-holes corresponds with a similar opening in the sleeper, so as to permit of the introduction of the external lock-piece, B, whereas in its second position, trans- 10 verse to the rail, the other lock-hole coincides with a second opening in the sleeper, thus permitting the introduction of the inner lock-piece, C, substantially as described above, and shown in the annexed drawings.

15 2. The combination of the resting-plate A, with an external lock-piece, B, of such a sec-

tion at N as will permit of its free motion in the opening of the sleeper and of such a section at M as will compel it to partake of the angular motion of the resting - plate A, substantially as shown in the annexed drawings. 20

3. The combination of the resting-plate and the external lock-piece, B, with one or more lock-pieces, C, secured by means of a ribbed key, D, and situate between the said key and 25 the rail, as specified.

LOUIS PHILIBERT GOFFIN.
EVARISTE VANRIET.
